UNITED STATES PATENT OFFICE.

WILLIAM BAILEY, OF BIRMINGHAM, ENGLAND, ASSIGNOR TO THE CROWN CORK AND SEAL CO., OF BALTIMORE, MARYLAND.

STOPPERING CROWN OR CAP FOR BOTTLES AND THE LIKE.

1,110,862.

Specification of Letters Patent. Patented Sept. 15, 1914.

Original application filed November 22, 1909, Serial No. 529,471. Divided and this application filed March 31, 1910. Serial No. 552,703.

To all whom it may concern:

Be it known, that I, WILLIAM BAILEY, a subject of the King of Great Britain, residing at Birmingham, Warwick, England, have invented certain new and useful Improvements in Stoppering Crowns or Caps for Bottles and the Like, of which the following is a specification, being a division of the application filed by me November 22, 10 1909, No. 529,471.

My invention relates to bottle stoppering crowns or caps, in which a disk of cork or other material is used as a packing to insure a tight joint when the cap is pressed upon 15 and secured to the bottle.

This invention is designed especially for that form of bottle stopper now well known as the "crown" in which is placed a cork disk as a packing or seal and the surrounding flange is compressed against a rib on the mouth of the bottle.

It is well known that it is desirable to cover the surface of this packing either to prevent contamination of the contents of the 25 bottle, or to prevent leakage through the pores or defects of the sealing disk.

My said invention consists of a special covering for this sealing disk the nature of which is adapted to the special conditions 30 of this kind of bottle stopper.

It is well known that this form of stopper (the "crown") is made in such enormous quantities as to require for the assembling as well as the making of the parts, the use 35 of machinery, and therefore the sealing disk, which is one of the component parts, is handled as a unit, and placed as such within the cap by the assembling machine.

I have therefore sought to effectively cover 40 the sealing disk, and cheaply, as is necessary, so that it remains, with the covering, as a unit, capable of manipulation as the assembling of the uncovered disk has been heretofore handled. Further, the sealing

45 requires that the disk must be sensitively yielding, and the covering must not interfere with this quality. To these ends I have covered the disk with foil, usually what is called "tin foil", a material cheap and impervious, and which can be wrapped so closely upon the exposed face of the sealing disk, and around its edges, and in part or whole upon its rear or inner face, that by its 50 lightness and pliability it will adhere there-

to. Thus wrapped closely upon the sealing 55 disk, this disk may be assembled with the cap, without disarrangement of the covering.

The invention is illustrated in the accompanying drawing in which,

Figure 1 is a sectional view of the improved washer or disk forming a part of my invention; Fig. 2 is a sectional view of a stopper constructed according to my invention; Fig. 3 is a side elevation of the cap 65 or crown; Fig. 4 is a plan view of the cap or crown; Fig. 5 is a view similar to Fig. 2 of another form of my invention in which the thin metal or tin foil covering for the cork disk or washer is provided with corrugations on its face; Fig. 6 is a plan view of the form of the invention shown in Fig. 5.

In these drawings, 1 indicates a washer or packing of compressible material, preferably cork, and of a size and form adapted 70 to fit within a metallic stoppering crown or cap, and 2 indicates a thin covering, such as foil, for the said washer having a portion extending over the entire exposed face of the compressible disk or washer over and 75 around its edge or periphery, and extending also partly over the other or rear face of the washer or cork disk, as indicated at 3. By the nature and form of the covering thus wrapped upon the disk it is held thereon so 80 that these parts constitute, in effect, one body, and can be handled as such, the thin covering or foil being maintained in position by its engagement with the faces of the cork disk or washer, as shown in Fig. 1, no 85 adhesive material being necessary to hold the parts together.

In Fig. 2 I show the cork disk or washer constructed according to my invention in place within the cap or crown, and it will 90 be seen that that face of the washer or disk which is directed toward the interior of the bottle, and which would be otherwise exposed to the contents of the bottle, is completely covered by the foil or thin metal, and 95 that the overlying flange or edge 3 of the foil lies between the washer and the main portion of the cap or crown. It will be seen also that the foil incloses the edge of the washer, extending, as it does, between said 100 edge and the adjacent wall of the cap or crown.

As shown in Figs. 5 and 6, I may pro-

vide the tin foil or metallic envelop of the compressible washer with corrugations, so that the metal would then be able, without tearing to undergo tension which might result from the expansion of the subjacent cork washer in case of excessive pressure at the time of stoppering.

I use the term foil with reference to its pliability or yielding nature, and capacity to cling to the disk when wrapped upon it without regard to the special material of which it is composed.

I claim as my invention:—

1. The herein described article comprising a metallic crown or cap having a downwardly extending outside flange adapted to engage with the neck of the bottle, and a compressible sealing disk located therein, said sealing disk being covered with foil wrapped over its exposed face and over its edge, and upon its rear face, substantially as described.

2. The described article consisting of a crown or cap and a sealing disk therein, said disk being covered with foil corrugated on its exposed face and extending over the edge and upon the rear face of the disk, substantially as described.

3. The herein described article comprising a metallic crown or cap having a downwardly extending outside flange adapted to engage with the neck of the bottle, and a compressible sealing disk located therein, said sealing disk being covered with flexible waterproof material wrapped over its exposed face and over its edge, and upon its rear face.

In testimony whereof, I affix my signature in presence of two witnesses.

WILLIAM BAILEY.

Witnesses:

T. SELBY WARDLE,
J. WILLIAM PATCHING.
